CLAMP

Daniel V. Holman, 2440 Bennett Ave., Evanston, Ill.

Filed Oct. 25, 1961, Ser. No. 67,256

Term of patent 14 years

(Cl. D54—13)

FIGURE 1 is a side elevational view of a clamp embodying my new design, the side opposite being a mirror image thereof;

FIG. 2 is a front elevational view thereof;

FIG. 3 is a rear elevational view thereof;

FIG. 4 is a top plan view thereof; and

FIG. 5 is a bottom plan view thereof.

The dominant features of my design reside in the portions shown in full lines.

I claim:

The ornamental design for a clamp, substantially as shown and described.
